ASSIGNORS TO PACKAGE MACHINERY COMPANY, OF SPRINGFIELD, MASSA-
CHUSETTS, A CORPORATION OF MASSACHUSETTS.

WRAPPING-MACHINE.

1,313,863.

Specification of Letters Patent. Patented Aug. 19, 1919.

Application filed February 5, 1919. Serial No. 275,220.

To all whom it may concern:

Be it known that we, ELMER L. SMITH and ARTHUR E. PHELON, citizens of the United States of America, residing at Springfield, 5 in the county of Hampden and State of Massachusetts, have invented certain new and useful Improvements in Wrapping-Machines, of which the following is a specification.

10 This invention relates generally to improvements in wrapping machines.

While the improvements are capable of general application, they are particularly advantageous in machines for wrapping relatively thin articles. For example, among the many uses, of which the improved machine is capable, may be mentioned the wrapping of cakes of chocolate and the like. Chocolate bars have during the past few

20 years gradually diminished in thickness until the bars have come to be very thin and sometimes not greatly thicker than a post card. These thin articles, being also readily frangible, are difficult to wrap. It has come

25 to be the custom to insert cards, such as post cards and the like, into the wrapped package for the purpose of stiffening the package. This practice does not wholly cure the difficulty, however, for the article, prior to

30 engagement with the card, must be carefully handled to avoid breakage. Moreover, the package, even when including the card, is still quite thin, so thin, in fact, that the tucking in of the narrow end extensions of 35 the wrapper is troublesome. The present invention is concerned among other things with improvements which are calculated to substantially reduce, if not to eliminate, the prior difficulties enumerated.

40 The invention has for an object to provide in a wrapping machine, specifically improved end tucking fingers, which are designed to successfully tuck in the narrow end extensions of the wrapper of relatively 45 thin articles.

The invention also has for an object to provide in a wrapping machine, a generally improved magazine for containing articles to be wrapped, and more particularly articles which are readily breakable.

50 A further object of the invention is to provide a magazine for articles to be

wrapped and a plunger to eject the articles,—the whole being directed to articles, which are relatively thin, and the magazine 55 combining by its location, with respect to the plunger, to assist in the certain ejection of thin (and oftentimes beveled) articles by a plunger, which is also necessarily thin (and oftentimes beveled) and which otherwise 60 would have a tendency to ride over or under the articles and defeat ejection thereof.

Another object of the invention is to provide a generally improved magazine for the reception of cards or the like, to be wrapped 65 with the articles, the construction being particularly characterized by improved means for preventing the return of the thin card into the magazine after it has once been ejected.

70 Another object of the invention is to provide improved means for feeding the cards to the articles, characterized in that the card feeding means combine with the article feeding means, to effectually feed the one in 75 properly timed relation with the other.

Another object of the invention is to provide end tucking fingers, which operate to make their tucks in the wrapper while the article is held in a pocket, the fingers, after 80 having been moved to make their folds, being arranged to remain in their moved positions, to subsequently lay down and crease other extensions of the wrapper.

85 Another object of the invention is to provide folding blades, which coöperate with one wall of the article retaining pocket of a tumble box, or the like, to fold extensions of the wrapper thereover, and thereby iron down the fold. These blades are further 90 arranged to remain in engagement with the folds during the ejection of the articles from the tumble box and are timed by, and co-operate with, the members which cause such 95 ejection.

A further object of the invention is to provide in a wrapping machine, having several intermittently movable tumble boxes arranged so that articles from one are transferred to the other, a simplified and generally improved means of effecting this transfer.

100 Other objects and advantages will appear in the following description and in the illus-

trative embodiment of the invention in the accompanying drawings, in which:—

Figure 1^a is a sectional elevational view of the left end of a wrapping machine embodying the invention;

Fig. 1^b is a sectional elevational view of the right end of the machine and is a continuation of Fig. 1^a. Figs. 1^a and 1^b should be imagined as joined together end to end to give a complete sectional elevation of the machine;

Figs. 2^a and 2^b are sectional plan views of Figs. 1^a and 1^b; and should be imagined as joined together end to end to give a complete plan view of the machine;

Fig. 3 is an enlarged fragmentary cross sectional view taken generally along the line 3 of Fig. 1^a;

Fig. 4 is a fragmentary rear elevational view of the machine;

Fig. 5 is a fragmentary sectional elevational view of the card machine;

Fig. 6 is a cross sectional view taken on the line 6—6 of Fig. 5;

Fig. 7 is a fragmentary cross sectional view taken on the line 7 of Fig. 2^b;

Fig. 8 is an enlarged fragmentary sectional view taken similarly to Fig. 1^b but showing a different relative positioning of parts and particularly the card and article feeding device;

Fig. 9 is a perspective view of the last named devices;

Fig. 10 is a fragmentary cross sectional view of the base of the article magazine;

Fig. 11 is a fragmentary sectional elevational view of the latter, taken similarly to Fig. 1^b but showing a different relative positioning of the parts;

Figs. 12, 13, and 14 are perspective views of the articles, showing successive stages in the wrapping thereof;

Fig. 15 is an end view of the partially wrapped article showing another stage in the wrapping;

Fig. 16 is a sectional plan view taken on the line 16—16 of Fig. 3;

Fig. 17 is a plan view of the completely wrapped article;

Fig. 18 is an elevational view of one of the end tucking fingers;

Fig. 19 is a diagrammatical view illustrative of the operation of the end tucking fingers; and

Fig. 20 is a fragmentary end elevational view of a partially wrapped article, illustrative of the preliminary step in the end tucking operations.

The machine in general, comprises, an improved magazine for the articles to be wrapped; a series of aligned but separated passages through which the articles to be wrapped may travel; article feeding mechanism to feed articles from the magazine to one of said passages; means through

which wrappers, labels, and the like may be successively supplied to, and positioned in the path of the articles; a series of spaced tumble boxes to transfer articles from one passage to another and assist in applying the wrapping material about the articles; end folding devices coöperating with one of the tumble boxes to complete the folding of the inner wrapper; mechanism to transport the articles from one tumble box to another; feeding means to supply cards or the like into the path of the articles and arranged so that the cards are positioned in correct relation with the articles and carried along therewith by the transporter mechanism; adhesive applying devices to gum the outer wrapper or label, whereby its edges may subsequently be sealed together; and a delivery conveyer to carry the wrapped articles from the machine and having, associated therewith, devices to hold the gummed seam from opening until the adhesive has had time to set.

Considering the machine somewhat more specifically in connection with the work which it, in its present illustrative embodiment, is adapted to perform, articles *a*, such as cakes of chocolate or the like, are fed in at one end of the machine and pass in a straight line to the other end thereof. During the travel of an article, an inner wrapper *b* is first fed into the path thereof, and, as the article is fed into the first tumble box, the wrapper *b* is laid partially around the sides of the article, as shown in Fig. 12, leaving one extension *c* to be subsequently laid down to completely enclose the sides of the articles. As the latter is removed from the first tumble box, the extension *c* is folded down, as shown in Fig. 13, so that the two edges of the wrapper *b* overlap. A card *d*, substantially of the same dimensions as the bottom face of article *a*, is fed to, and subsequently carried along with, the article. Card *d* covers the longitudinal overlapped seam of wrapper *b* (Fig. 13) and also functions as a stiffening member to prevent breakage of the article, which, when the latter is a thin cake of chocolate or the like, might otherwise occur. The article is now entirely enclosed except for its ends and, at each end, there are a pair of relatively narrow wrapper extensions *e* and a pair of relatively wide wrapper extensions *f*. The article *a*, wrapped and having the card *d* applied thereto, as shown in Fig. 13, is then fed into the second tumble box, which, as well as the other tumble boxes, moves intermittently. During an interval of rest of the second tumble box, the end extensions *e* are first laid down, the wrapping then appearing as shown in Fig. 14. The end extensions *f* are operated upon during the movement of the second tumble box from the position,

wherein the end folds *e* are made, to the position wherein the article is discharged from the second tumble box. The two folds *f* at each end of the article are first folded in the same direction until they both stand at right angles to the flat bottom face of the article, as shown in Fig. 15. As the article thus wrapped, is ejected from the second tumble box, the extensions *f*, which have been previously creased by the prior folding operation described, are laid down flat against card *d* on the bottom face of the article. The latter then passes into the third tumble box and in so doing a label *g*, substantially coextensive in length with the article, is partially wrapped about the sides thereof, in a manner exactly similar to that in which the inner wrapper *b* is applied, so that one projecting extension remains to be folded on ejection of the articles from the tumble box. Such fold is engaged, during a period of rest of the third tumble box, by an adhesive applying device, so that the label extensions, when folded by the ejection of the articles from this tumble box will adhere to that portion of the label on which it is overlapped, as shown in Fig. 17. The articles, now completely wrapped, are conveyed from the machine and the gummed overlapped seam *h* of label *g* is held from opening by suitable means until the adhesive has had time to set.

The general frame structure of the machine, together with the main driving connections therof, will first be described with particular reference to Figs. 1^a, 1^b, 2^a and 2^b. A represents a suitable supported table or bed plate, from which columns, as *i* (Fig. 2^a) and other columns, as *j* (Fig. 2^b) arise, as indicated. These columns *i* and *j* are connected by bars *k* (Figs. 1^a and 1^b) and these bars are intended as supports for the label and wrapper feeding mechanisms, respectively. The columns *i* and *j* and bars *k* have been largely omitted from the drawings, as well as the label and wrapper feeding mechanism with which the invention is not particularly concerned. The table A has a longitudinal opening *l* in its upper face to receive, and permit the movement of, the three tumble boxes. These tumble boxes, represented generally by 20, 21 and 22 are rotatably supported by horizontal shafts 23, 24, and 25, which span the opening *l* transversely and are suitably supported on either side thereof from table A. All of the tumble boxes are of generally similar construction and include a series, (four in this instance) of angularly spaced pockets 26, into or out of which the articles may be radially moved. The pockets 26 are provided with spaced parallel walls 27 to engage the top and bottom faces of the articles and these walls are substantially coextensive with such faces. At least one of the walls 27 is yield-

able, as indicated, and the pockets afforded by such walls are open at both ends and at both sides, to permit movement of the articles into and out of the pocket and to permit the end folding operations, respectively.

70

The several tumble boxes are driven intermittently by suitable steps of angular movement (in this instance steps of ninety degrees) in the following manner: The shaft 24 is provided at one end with a gear 28 (Figs. 2^a and 4) which is driven by a gear 29 (Fig. 4) mounted on a stud 30 supported on frame A. As illustrated, the ratio of gears 28 and 29 is such that one sixth of a revolution of the latter will cause one quarter of a revolution of the former. Also fixed to gear 29 is a Geneva cam 31, which is driven by a crank 32, fixed on a horizontal shaft 33, suitably supported below the table A. The arrangement is such that each revolution of shaft 33 will cause one sixth of a revolution of cam 31 and thus one quarter of a revolution of the shaft 24, which carries the tumble box 21. The latter turns in a counter clockwise direction (Fig. 1^a) and is arranged to drive the tumble boxes 20 and 22 in a reverse direction. Thus, shaft 24 is connected by miter gears (Fig. 2^a) with two axially aligned horizontal shafts 34 and 35, which turn in opposite directions but at the same speed and at the same speed as shaft 24. Shafts 34 and 35 are connected by miter gears (Figs. 2^a and 2^b) with the shafts 23 and 25, respectively, which turn in the same direction and at the same speed.

85

The described shaft 33 is driven by a chain 36 and suitable sprockets from a shaft 37 mounted below bed A, as shown in Fig. 1^a. The chain 36 also engages suitable sprockets on other parallel shafts, as a shaft 38 (Fig. 1^a) which is mounted above bed A in brackets *m* secured to and depending from the described bars *k*, and a shaft 39 (Fig. 1^b) which is rotatably supported beneath bed A. The chain 36 also engages an idler sprocket 40 (Fig. 1^a). The shaft 37 is the main power shaft of the machine and is adapted to be driven from suitable means by the pulley shown in Fig. 2^a. Shafts 38 and 39, as well as the tumble box driving shaft 33, function as camshafts, as will later appear in detail. There is also provided another camshaft 41 (Fig. 1^b) which is rotatably supported beneath bed A and driven by a chain 42, and suitable sprockets, from the described shaft 33.

90

Adjacent the right hand side of tumble box 20 (Fig. 1^b) are suitable chute forming members, one of which,—the lower member 44,—is rigidly supported from a bracket *n*, which spans the described opening *l* and is supported from bed A. Member 44 has its upper face substantially in the same horizontal plane as the lower wall 27 of that pocket 26 which lies adjacent the members.

130

Above the member 44 and in parallel relation therewith is a cross bar 45 which is rigidly supported at its ends from bracket *n* by screws 46 and spacer tubes 47. The top 5 wall of the chute or passage is formed by a plate 48 which is slidable vertically with relation to and is guided in the cross bar 45 by pins 49. The latter have heads 50 to limit the downward travel of plate 48 and springs 51 tend to yieldingly hold the plate 48 in its lowermost position. The plates 44 and 48 are, thus, maintained in spaced relation to afford a passage, through which articles and their wrappers may be fed as they 10 pass to the first tumble box 20.

Between the tumble boxes 20 and 21 is a second chute, which is alined with the chute just described. The stationary bottom wall 53 of this chute is formed by the horizontal 20 portion of an angle shaped plate, which extends transversely across opening *l* and is supported from bed A by a bracket *o*, to which the vertical portion of the angle plate is attached. The upper wall of the second 25 chute consists of a plate 54 yieldably supported from a cross bar 55, in a similar manner to that already described in connection with plate 48. The cross bar 55 is rigidly attached at its ends to two spaced and longitudinally disposed bars 56 (Figs. 1^b, 2^a and 2^b), which in turn are supported by brackets 30 *p* from bed A. In line with the left hand edge of plate 54, (Fig. 1^b) is a vertical plate 57, the upper edge of which is disposed substantially in the horizontal plane in which the bottom wall 53 is disposed. The latter has its forward (left hand in Fig. 1^b) edge spaced from plate 57 to afford an opening 58, through which the cards *d* may be fed as 35 40 will appear. The plate 57 is supported from one end of a bar 58' (Fig. 7) which is secured at its other end to bed A.

Between the tumble boxes 21 and 22 is a third chute, which includes a fixed lower 45 wall 59 and a yieldable upper wall 60, constructed and mounted in the same way as the walls 44 and 48 of the first chute above described.

The magazine for articles to be wrapped 50 will now be described with reference to Figs. 1^b, 10 and 11. As shown in 1^b, the magazine is arranged closely adjacent the chute forming members 44 and 48. The magazine consists merely of a series of suitable uprights 55 61, which encompass the four sides of the articles and hold them properly alined for ejection into and through the first chute and into the pockets 26 of the tumble box 20. The base of the magazine is of grid-like 60 formation and includes a series of thin longitudinally disposed bars 62 (Fig. 10) which are arranged in spaced parallel relation and supported by a cross bar 63 (Fig. 1^b). Cross bar 63 is attached at its ends to two laterally 65 spaced upstanding brackets *q* which are se-

cured to the upper face of bed A. The magazine is arranged to receive a stack of the articles *a* with the lowermost article of the stack resting upon bars 62. The grid-like formation of the base of the magazine 70 is advantageous where, as is frequently the case, the articles are of a readily frangible nature, such as cakes of chcolocate or the like. Such cakes are now, quite usually very thin, even around the margins of the cake 75 and generally, except for such margins, the interior of the cake is much thinner. The cakes, therefore, may become chipped and broken and the grid-like base of the magazine allows the broken pieces to drop 80 through the spaces between bars 62 rather than to remain on the base and clog the magazine. The uprights 61 of the latter are purposely inclined to relieve the lower cakes from as much as possible of the weight of 85 the stack. The magazine otherwise is of usual construction and is designed so that the lowermost article of the stack is withdrawn by suitable means, as a plunger, which serves to support the remainder of the 90 stack during its travel in under the magazine. The latter has associated with its exit orifice a yieldable keeper 64 to prevent articles, other than the lowermost of the stack, from being ejected with the lowermost article. 95

The mechanism for feeding the inner wrappers *b* may be of any of the many types now well known in the art. Such mechanism has not been illustrated since it is unnecessary to an understanding of the invention. Any suitable wrapper feeding mechanism may be supported from the cross bars *k* and be arranged to feed the wrappers *b* in continuous strip form, vertically downwardly into a guide chute 65 (Fig. 1^b). Such chute is supported by a bracket *r* from the columns *j* and, spaced vertically below chute 65 and below bed A, is a second alined chute 66, into which the lower end of the 105 wrapper strip passes. The chutes 65 and 66 are arranged closely adjacent the exit of the article magazine on one side and closely adjacent the horizontal chute-forming members 44 and 48 on the other side. A part of 110 the keeper 64 and an upturned extension 67 of the member 48 coperate to guide the wrapper strip from chute 65 into chute 66.

Means are provided to sever the wrapper strip at properly timed intervals to leave 120 merely an individual wrapper resting in chute 66 with its upper end projecting vertically therefrom and lying between the keeper 64 and extension 67. Such means includes a fixed knife blade 68, disposed on one 125 side of the path of the wrapper *b* and secured to the bracket *r*. A movable blade 69 is pivoted at 70 to bracket *r* and is adapted to be moved toward and away from blade 68 to sever the wrapper strip (Figs. 1^b and 130

2^b). As shown in Fig. 2^b, the blade 69 is connected by a link 71 to the upper end of a lever 72, which, as shown in Fig. 4, is pivoted intermediate its ends to bed A. The 5 lower end of lever 72 is connected to one end of a member 73 and the other end of the latter is forked to engage the described shaft 39 for guiding purposes. Shaft 39 has fixed thereon a cam 74 which has a suitable path 10 therein to receive a roll on member 73, whereby the blade 69 may be actuated in an obvious manner.

The means, for feeding the articles *a* from the magazine against the wrapper *b* and 15 through the chute forming members 44 and 48 into the pockets 26 of tumble box 20, will now be described with particular reference to Figs. 1^b and 2^b. This means comprises a thin, flat plunger 75 which is supported at 20 its rear (right hand as viewed in Fig. 1^b) end by a bar 76, which in turn is slideable horizontally in suitable ways 77 provided in the spaced brackets *q* above described. The bar 76 is connected by a link 78 to the 25 upper end of a lever 79, which is pivoted intermediate its ends to a bracket secured to frame A. The lower end of lever 79 is connected to one end of a member 80. The other end of the latter is suitably slotted to 30 engage the described shaft 41 for guiding purposes and the member carries a suitable roll to ride in a cam path formed in one side (the rear as viewed in Fig. 1^b) of a disk 81 fixed to shaft 41. This cam path is so 35 designed as to move the plunger 75 forwardly to eject an article from the magazine against the wrapper *b*, shortly after the severing action of blade 69, and to force the article against its wrapper *b* and carry the 40 former, with the partially folded wrapper, through the chute forming members 44 and 48 and into a pocket 26 of tumble box 20. The plunger then recedes until its article engaging end lies to the right of the article 45 magazine and dwells in such position until a succeeding cycle of operation.

The articles *a* are commonly beveled, as shown in Figs. 1^b and 11. Where the articles *a* are readily frangible, as when the 50 articles consist of thin cakes of chocolate or the like, it is essential that the article engaging end of the plunger 75 be correspondingly beveled, for otherwise, the thin edge of the articles engaged by the plunger might 55 be crushed and broken. The beveling of the plunger, however, has a marked disadvantage. Thus, with the beveled surfaces arranged as shown in Fig. 11, the plunger tends to cam the articles upwardly while, if 60 the beveled surfaces were reversely arranged, the plunger, being thin and readily flexed, would tend to ride over the lowermost article *a*. To overcome this disadvantage the article magazine is inclined to the vertical 65 and arranged to lean toward the rear of the

plunger. This arrangement tends to concentrate the weight of the stack on the rear corner of the lowermost article *a* so that it is not readily cammed upwardly by the plunger 75. The same arrangement would serve 70 equally well when the coacting beveled surfaces were reversely arranged as above described.

The article *a*, when forced into the tumble box 20 has the wrapper *b* partially laid about 75 its sides, leaving merely one wrapper extension *c* to be subsequently laid down. The tumble box 20 turns intermittently in a clockwise direction and the article and its wrapper eventually become positioned adjacent, and in alignment with, the chute forming members 53 and 54. As the tumble box approaches the described position, the projecting fold *c* engages a plate 82 and is laid down into the position shown in Fig. 1^b, so 80 that the article, when ejected from the tumble box 20 into the chute formed by members 53 and 54, will be completely inclosed by its wrapper. Plate 82 is pivoted and yieldingly urged into the illustrated position, in the usual manner, by means not shown, and acts to yieldingly hold the extension *c* during ejection of the article so 85 that the extension is drawn tightly about the article and laid flatly and smoothly 90 thereagainst.

The means for moving the articles from the tumble box 20, through the chute just described and into the tumble box 21 will next be described. Referring to Figs. 2^a and 2^b, 100 two rods 83 are mounted in spaced parallel relation, one on each side of the described opening *l* to slide longitudinally, but not to turn, in the brackets *p* already described, and in other brackets *p'*. Fulcrumed intermediate their ends on the described shaft 33 (Fig. 1^a) are two axially spaced levers 84, one arranged closely adjacent each longitudinal edge of the opening *l*. Each lever 84 is connected at its upper end by a link 85 to the adjacent rod 83, whereby the rods may be reciprocated upon a swinging movement of the levers. The latter are interconnected at their lower ends by a cross bar 86 and such bar is pivotally connected to one 105 end of an arm 87. The other end of the latter is slotted to engage the described shaft 41 for guiding purposes, and also bears a roll to ride in a suitable cam path formed in the front face of the described disk 81 (Fig. 1^b). This cam path is so designed that the rods 83 are held stationary during the intervals 110 of movement of the tumble boxes and move forwardly (to the left as viewed in Figs. 1^b, 1^a, 2^a and 2^b) and back again during the intervals of rest of the tumble boxes. The stroke of the rods is substantially equal to the distance between the centers of the two 115 adjacent pockets of successive tumble boxes. On each rod 83 there is fixed an arm 88 120

(Fig. 2^b) and the two arms 88 extend toward one another and overhang the opening 7. The arms 88 are so disposed that they travel through the pocket 26 of tumble box 20 and 5 remove the article and its wrapper therefrom, carrying them through the chute forming members 53 and 54 and into the tumble box 21.

During the travel of the articles from the 10 tumble box 20 to the tumble box 21, the cards *d* are fed thereto, by means which will now be described. The cards *d* are contained in a magazine 89 located at the rear of bed A (Fig. 4). The cards *d*, as shown in Fig. 5, 15 are stacked vertically in the magazine and the lowermost card of the stack rests upon a plate 90, which is secured to a plunger 91 mounted to slide on a guide 92 secured to a bracket *s* supported from bed A. A bar 93 20 extends laterally across plunger 91 intermediate its ends and extends above plate 90 a distance slightly less than the thickness of a card *d*. Thus, as plunger 91 moves to the right (Fig. 5) the bar 93 will eject the lowest 25 card *d* and the plate 90 will underlie the card during the ejection movement. The upper face of plunger 91 serves to support the stack of cards during such movement, the stack dropping slightly as the plunger 30 returns so that the lowermost card is again supported on plate 90. The plunger 91 is reciprocated in a line parallel to the travel of the articles, as clearly indicated in Fig. 2^b. The means for reciprocating the plunger 91 best appear in Fig. 4. Projecting from one side of the plunger is a pin 94, which is received in the forked upper end of a lever 95, pivoted at 96, and the lever is connected intermediate its ends by a link 97 35 to a crank 98 on the described camshaft 39.

The magazine 89, being at a distance from the path of the articles *a*, means are provided to carry the cards into such path. Spaced parallel tracks 99 (Fig. 2^b) extend 40 laterally of bed A from a position adjacent magazine 89 (Figs. 4 and 5) to a position adjacent the described plate 57 (Fig. 7). Side guide plates 100 are secured to the tracks 99 and project thereabove to guide 45 the cards in their travel. Between the tracks 99, a conveyer chain 101 is provided (Fig. 2) and this chain is arranged to travel over a sprocket 102 (Fig. 4) on a shaft 103, rotatably supported at the rear of bed A, 50 and driven by a chain 104 and suitable sprockets from the described shaft 35, which is intermittently operated. The chain 101 is guided at its other end by an idler sprocket 105 (Fig. 7), rotatably supported from bed 55 A. Chain 101 has a plurality of lugs 106 mounted in suitably spaced relation thereon to engage the cards *d*, ejected from the magazine 89, and propel them along the trackways 99.

60 To prevent the cards *d*, after being ejected

from magazine 89, from returning with the plunger plate 90, the following means are provided: A roll 107 (Figs. 4 and 5), preferably of rubber or the like, is mounted on the magazine adjacent its exit orifice. The 70 lowermost point on the periphery of roll 107 is substantially in the same horizontal plane as the upper face of the lowermost card *d* of the stack. On each side of roll 107 are blocks 108, which are secured to and 75 project above one of the trackways 99. The upper face of each block 108 is beveled and slants downwardly toward the magazine so that the lowest point of this beveled face lies substantially in the same horizontal 80 plane as the lower face of the lowermost card *d*, while the highest point in such face lies above the lowermost point in the periphery of roll 107. Consequently, as a card *d* is ejected from the magazine, its ends 85 are cammed upwardly and flexed by the blocks 108, so that when the card leaves the block it may then snap downwardly to prevent a return movement.

The cards are intermittently conveyed 90 along tracks 99 by chains 101 and are successively delivered at properly timed intervals upon a plunger 109 (Fig. 7). A stop 110, secured to bed A, prevents overtravel of the cards *d* on plunger 109 and positions 95 them so that their end edges lie in substantially the same vertical plane as the end edges of the articles *a*, when the latter are positioned between the chute forming members 53 and 54 already described. As shown 100 in Fig. 1^b, the card *d*, thus deposited on plunger 109, is positioned between the vertical plate 57 and the vertical portion of the plate 53. The card *d*, however, lies below the horizontal plane of travel of articles *a*. 105 The plunger 109 has a rectangular stem 111, which is mounted for vertical reciprocation in a bracket *t*, on frame A. A link 112 is connected at its upper end to stem 111 and at its lower end to one arm of a bell crank 110 lever 113, which is mounted on a rock shaft 114. The other arm of lever 113 carries a roll, which rides in a path cam 115. This cam is so constructed as to raise plunger 109, immediately after the tumble box 20 115 comes to rest, to carry the card *d* substantially against the bottom of plate 53. The cards *d* are substantially co-extensive in length with the articles while the plunger 109 and plate 53 are of 120 less length than the articles. Fingers 116 are provided on each of the described article conveying arms 88 in such position as to engage the rear edge of card *d*, while held below but closely adjacent the plate 53, and 125 carry it forwardly with the articles *a* and their wrappers, all as clearly shown in Figs. 8 and 9. One wall of each pocket 26 is slotted as shown at 116' in Fig. 2^b to permit the free passage of fingers 116, and the 130

5 fingers 116 are arranged one on each side of plate 53, which as described is of less length than the card *d*, so that the plate 53 does not interfere with the movement of the fingers 116. The inner upper edge of plate 57 is rounded so that the card *d*, when thus conveyed, may readily rise through the opening 58 into the chute in which the articles are conveyed. The cam 115 is so 10 constructed as to lower plunger 109, after the fingers 116 have engaged the card *d* and moved it sufficiently so that the forward edge has passed over the top of plate 57. The cam 115 then holds the plunger 109 15 stationary in its lower position until the tumble box 20 again comes to rest. The card *d* is applied to the wrapper *b* of article *a*, by the means just described, as shown in Fig. 13, and the article, wrapper and card 20 are carried in this condition into the second tumble box 21.

25 The next folding operation consists in making the end tucks *e* (Fig. 14). This operation is performed while the article is at rest in the uppermost pocket 26 of tumble box 21, by the following mechanism. The entire end tucking mechanism is supported in the described brackets *m* from the cross bars *k*. Referring to Fig. 3, above the shaft 30 38, which as already described is mounted in and extends between the brackets *m*, is a rock shaft 117, which is mounted to oscillate in the brackets. Below the shaft 38, a rod 118 is fixed to, and extends between the 35 brackets *m*. Fixed to and depending from rod 118 are a pair of brackets *u* and to each of the latter is fixed a section shaped plate 119 (Fig. 1^a). The plates 119 are spaced, one from another by a distance substantially 40 equal to the length of the articles *a*, so that the tumble box 21 can move freely therebetween. Each plate 119 has a right angularly and outwardly turned flange 120 and the articles come to rest in their upper position 45 with the forward wrapper extensions *f* lying substantially contiguous with these flanges, all the extensions *e* and *f* projecting outwardly beyond the plates 119.

50 In each bracket *u* are upper and lower horizontal shafts 121 and 122, which are arranged one above another in vertical alignment and are also arranged at right angles to the drive shaft 38 and rock shaft 117. On one end of each of the shafts 121 and 122 are fixed end tucking fingers 123. Near their other ends, the shafts 121 and 122 have fixed thereon segmental gears 124 (Figs. 1^a and 3) the gear on each shaft 121 meshing with the gear on the shaft 122 55 therebelow, so that a rocking of one shaft in one direction will simultaneously rock the other shaft in the opposite direction. Adjacent the gears 124 and on each of the shafts, 121, there is fixed an arm 125. The 60 arms 125 are connected by upwardly extend-

ing links 126 to levers 127 fixed on the rock shaft 117, so that a rocking of the latter will 70 actuate all four of the end tucking fingers 123. The rock shaft 117 has fixed on one end thereof a depending arm 128, which carries a suitable roll to engage in a path cam 129, fixed on the drive shaft 38. The cam 129 is so constructed that the fingers 123 are swung toward one another just after the tumble box 21 has come to rest, whereby the 75 end tucks *e* are made, and to then hold the fingers in their moved position until the tumble box commences its next step of movement, and to thereafter return the fingers to the illustrated position before the tumble box again comes to rest.

80 The fingers 123 are specially constructed as best shown in Figs. 18 and 19. The wrapper engaging ends of these fingers are of wedge-like character, having relatively 85 thin, and somewhat pointed, outer ends 131, which diverge outwardly toward the pivots of the fingers to form relatively thick portions 130. The latter portions are arranged to first engage the wrapper extension *e* and 90 at the outer edges thereof, as indicated in Fig. 19. Such preliminary engagement of the wrapper extensions by the thick portions 130 operates to force out and spread the extensions, substantially as shown in Fig. 20. 95 This is particularly advantageous where, as here, the articles are very thin, for by first spreading out the extensions *e* preliminarily, it is insured that the ends 131, which must of necessity be very thin, will properly engage the extensions *e*. Without this preliminary fanning out of the extensions, and with very thin packages, the thin end tucking portions 131 would still engage the extensions but the latter might well be 100 forced to one side or the other of the fingers so that the extensions *e* would not be properly tucked in.

105 The means for laying down the larger end wrapper extensions *f* will now be described. This folding operation is effected in several stages. First, it has been already described that the fingers 123 remain in their inner positions while the tumble box 21 commences to move. By this arrangement the rearward extensions *f* are bent at right angles to the major faces of the articles and the line of fold is effectively creased. The forward extensions *f* are similarly laid down and creased, as the tumble 110 box commences to move, by means of the described flanges 120. These flanges, however, might also be relied on to lay down the rearward extensions *f* but they could not act to effectively crease the line of fold 115 thereof. Therefore the end tucking fingers 123 are desirably arranged to dwell in their inner positions to accomplish this function.

120 As the tumble box 21 moves to carry the articles from the end tucking position to a 130

position, wherein they may be discharged from the tumble box 21 into the chute formed by members 59 and 60, the extensions *f*, now preliminarily folded in the manner shown in Fig. 15, are held in such relation by the two spaced arcuate plates 119. The latter serve during the travel of the articles therebetween to iron down the folds so that they tend to stay put.

- 10 It now remains to lay down flat against the under side of the articles, those portions of the extensions *f*, which as shown in Fig. 15, project above the bottom of the articles. This operation is accomplished while the 15 tumble box 21 is at rest and just as the articles are about to be ejected therefrom. As shown in Figs. 3 and 16, a bell crank lever 132 is pivoted to each of the described brackets *u* to swing in a horizontal plane. One arm 20 of each lever 132 carries a folding blade 133 and these blades are movable beneath the plates 119 and can swing inwardly toward one another, and over the upper plate 27' of the pocket 26 as shown in Figs. 1^a and 16. 25 The blades are arranged to swing in very close relation to the upper surface of plate 27' and to lay down the remaining portions of extensions *f* over and flat against the plate. 30 These folding blades 133 are automatically operated at the proper time under the control of the members, which function to remove the articles from tumble box 21. Such members consist of fingers 134, which 35 are fixed to the rods 83, as shown in Fig. 3, and function in a manner exactly similar to the fingers 88 already described. The fingers 134 move from the position, illustrated in Fig. 16, in the direction of the 40 arrow to engage and eject the articles. The short arm of each bell crank 132 has a depending pin 135 which extends below the top surface of the adjacent finger 134, as shown in Fig. 3. Each of the last named 45 arms is connected by a spring 136 with the adjacent stationary plate 119, and the springs tend to swing the folding blades 133 toward one another in the manner just described. The springs 136, however, are 50 held by the engagement of pins 135 with the fingers 134, so that the blades 133 remain in their illustrated position until the fingers move forwardly. The forward movement of the latter allows the blades 133 55 to be swung toward one another to make the folds described. The inward movement of blades 133 is limited by the engagement of projections 137 (Figs. 1^b and 16) with the outer faces of plates 119. The 60 blades 133, then, remain in their moved positions, during the ejection of the articles from the tumble box 21, and hold the last folded portions of extensions *f* until they 65 are engaged by the spring pressed chute forming member 60. The fingers 134 carry

the articles with their wrappers and cards *d* through the chute formed by members 59 and 60 and into the third tumble box 22.

As the articles pass into the tumble box 22, they are carried against a label or outer 70 wrapper *g*, which is fed by suitable means (not shown) into the chutes 139 and 140 (Fig. 1^a) arranged above and below the path of the articles, respectively. As an article is carried against the wrapper *g*, it 75 passes between two rolls 141, one of which (the upper) is supported by a spring arm 142. The latter is arranged to be slightly flexed upwardly by the articles in passing, and therefore yieldingly presses the articles 80 against the lower roll 141. The two rolls 141, together, function to create a slight drag on the wrapper *g*, to stretch the same tightly about the articles as they pass into the tumble box 22. The wrapper *g* is folded 85 about the articles, as they are forced into tumble box 22, in a similar manner to that in which the inner wrapper *b* is applied, for example, as shown in connection with the latter in Fig. 12. Thus, one extension 90 *f*' is left projecting from the pocket of the tumble box. As the latter moves on its next step of movement the lower end of extension *f*' is carried into engagement with a resilient plate 142 (Fig. 1^a), which plate 95 is suitably secured to bed A, as indicated. The tumble box 22 comes to rest with the extension *f*' depending vertically downward and with its lower end contiguous with the plate 142.

100 In such position adhesive is applied to the lower end of extension *f*' by the following means: A glue box 143 is removably secured to the upper end of an arm 144 which in turn is secured at its lower end to a 105 lever 145 pivotally mounted at 146. The lever is pivotally connected to one end of an arm 147 and the other end of the latter is forked to engage the described cam shaft 33 for guiding purposes. The arm 147 110 is further provided with a suitable roll to ride in a path cam 148 fixed to the shaft 33. The glue box 143 is provided with the usual roll (not shown), which receives the adhesive and engages the extension *f*' to 115 gum the latter. The cam 148 is so constructed as to hold the glue box 143, and its roll, stationary during the intervals of movement of the tumble box 22 and in such position (to the right of the position 120 illustrated in Fig. 1^a) that the wrapper extension *f*' can freely pass. During the intervals of rest of the turret, the cam 148 causes the glue box 143 to be swung into the illustrated position so that its roll contacts the extension *f*', which is yieldingly pressed thereagainst by the plate 142. Thus, adhesive may be applied to the extensions *f*'.

125 It is generally desired to turn the glue box 130

roll step by step and, to this end, a ratchet 149 is fixed to one end of the shaft 150 of said roll. On the other end of shaft 150 an arm 152 is loosely mounted at a point intermediate its ends. One end of arm 152 is pivoted to bed A at 153 and the other end bears a pawl 154 to engage the ratchet. As the glue box 143 swings toward the wrapper extension *f*, the arm 152 is swung, relatively thereto, so that pawl 154 turns the ratchet in a clockwise direction. During the return movement of the glue box, the pawl 154 rides idly over the teeth of ratchet 149 and the latter is held from counterclockwise rotation by a holding pawl 155 which is pivoted to one wall of the glue box.

As the tumble box 22 turns through its next step of movement, the articles are carried into line with a discharge chute 156, and when the articles are ejected from the tumble box into this chute, the gummed extension *f* is laid down and overlapped upon the other end of wrapper *g* to form the seam *h* and complete the wrapping. The ejection of the articles from the tumble box 22 is effected by two fingers 157 fixed to the described reciprocable rods 83. These fingers operate during the intervals of rest of the tumble box to first carry the articles into chute 156 and to then return, leaving the articles so positioned that their rear edges lie substantially vertically above the axis of a sprocket wheel 158, rotatably supported from bed A. The chute 156 is composed of a series of spaced parallel plates 159 (Figs. 1^a and 2^a), which form the top wall, and like spring pressed plates 160, which form the bottom wall at the entrance end of the chute. The bottom wall for the remainder of the chute is shown as composed of a brush 161. A sprocket chain 162, driven by a sprocket 163 from the main drive shaft 37, travels over the described sprocket 158, and at least one other sprocket (not shown) and is arranged so that the upper lap of the chain is parallel with the walls of chute 156. Lugs 164 are provided, at suitably spaced intervals on chain 162, to engage the wrapped articles deposited on member 160 and carry them along the chute 156. The wrapped articles are held by the walls of chute 156 to prevent the gummed seam *h* of wrapper *g* from opening, and the chute 156 is made of suitable length, and the speed of chains 162 is so chosen, that the wrapped articles are held in the chute for a sufficient interval to allow the adhesive to set.

The operation of the machine will largely appear from the foregoing description and it remains only to briefly describe the manner in which the various elements are co-ordinated and caused to work in properly timed relation. The several cam shafts 38, 39, 38, 39 and 41 are all driven continuously at

the same speed, while the several tumble boxes 20, 21 and 22 turn intermittently but simultaneously. The tumble box drive is co-ordinated with the cam-shaft drive since it is effected, through the Geneva cam arrangement described, from the cam shaft 33. One revolution of the latter will cause one cycle of operation of the tumble boxes,—including both the interval of motion and the interval of rest. During each revolution of each cam shaft, the various cams described force the various mechanisms, which they control, through one complete cycle, so that the desired co-ordination is effected. The card transporting mechanism,—the chains 101,—operate intermittently in synchronism with the tumble boxes since they are driven from the tumble box drive. The delivery conveyer,—the chain 162,—is driven continuously but its surface speed is so chosen that it moves a distance equal to that obtaining between successive lugs 164, during one cycle of operation of the various cams and tumble boxes.

The invention has been disclosed herein in a preferred embodiment for the purposes of illustration but the scope of the invention is defined by the appended claims rather than by the foregoing description.

What I claim is:

1. In a wrapping machine, a folding finger having an outwardly tapering wrapper engaging end and arranged to first engage the wrapper extension near its outer end and with the thicker portion of the finger, whereby the extension is first spread to insure the subsequent engagement of the thin extreme end of the finger with the extension. 100
2. In a wrapping machine, a folding finger having a thin end adapted to fold a narrow end extension of the wrapper of the articles and a thicker portion at a distance from such end to preliminarily engage the extension and spread it in fanlike form for subsequent engagement by the thin end. 105
3. In a wrapping machine, means to wrap an article leaving oppositely disposed pairs of wrapper extensions projecting from an end of the article, some of which extensions are relatively narrow with relation to the other extensions, and means to fold the relatively narrow extensions; said last named means comprising fingers mounted to move in the plane substantially parallel with that of the wider extensions and having wrapper engaging ends which taper from relatively thick portions to relatively thin portions at the tips of the fingers, the latter arranged to be so moved that the thick portions first engage the narrow extensions near the ends thereof and spread such extensions to insure the subsequent engagement of the thin portions therewith to properly complete the folding operation. 115
4. In a wrapping machine, an intermit- 120
5. In a wrapping machine, an intermit- 125
6. In a wrapping machine, an intermit- 130

- tently movable carrier having a pocket in which a partially wrapped article may be positioned with substantially tubular wrapper extensions projecting beyond the ends thereof, a pair of folding fingers on each side of the carrier, means operable while the latter is at rest to move the fingers of each pair in opposite directions to engage the extensions and tuck in opposite portions thereof against the article, said means arranged to hold the fingers in their moved positions to act as abutments and lay down other portions of the wrapper extensions, on movement of the carrier.
- 5 15. In a wrapping machine, an intermittently movable carrier, having a pocket in which a partially wrapped article may be positioned with substantially tubular wrapper extensions projecting beyond the ends thereof, a pair of folding fingers on each side of the carrier, means operable while the latter is at rest to move the fingers of each pair in opposite directions to engage the extensions and tuck in opposite portions thereof against the article, said means arranged to hold the fingers in their moved positions to act as abutments and lay down other portions of the wrapper extensions on movement of the carrier, and stationary abutments to engage and fold the remaining portions of said extensions on movement of the carrier.
- 20 25. In a wrapping machine, an intermittently movable carrier, having a pocket in which a partially wrapped article may be positioned with substantially tubular wrapper extensions projecting beyond the ends thereof, a pair of folding fingers on each side of the carrier, means operable while the latter is at rest to move the fingers of each pair in opposite directions to engage the extensions and tuck in opposite portions thereof against the article, said means arranged to hold the fingers in their moved positions to act as abutments and lay down other portions of the wrapper extensions on movement of the carrier, and stationary abutments to engage and fold the remaining portions of said extensions on movement of the carrier.
- 30 35. In a wrapping machine, an intermittently movable carrier, having a pocket in which a partially wrapped article may be positioned with substantially tubular wrapper extensions projecting beyond the ends thereof, a pair of folding fingers on each side of the carrier, means operable while the latter is at rest to move the fingers of each pair in opposite directions to engage the extensions and tuck in opposite portions thereof against the article, said means arranged to hold the fingers in their moved positions to act as abutments and lay down other portions of the wrapper extensions on movement of the carrier, stationary abutments to engage and fold the remaining portions of said extensions on movement of the carrier, and means to subsequently engage and hold those portions folded by said abutments and said fingers.
- 40 45. In a wrapping machine an intermittently movable carrier having a pocket in which a partially wrapped article may be positioned with a substantially tubular wrapper extension projecting from each end thereof, a pair folding fingers on each side of the carrier, each pair operable while the carrier is at rest to move toward one another to engage and tuck in opposite portions of said extensions leaving other portions to be subsequently folded, and means to move said fingers into folding position and hold them in such position until the carrier has started

on its next step of movement, whereby the fingers function to lay down and crease one of said extensions.

8. In a wrapping machine, an intermittently movable carrier having a pocket in which a partially wrapped article may be positioned leaving a pair of relatively narrow and oppositely arranged end wrapper extensions and a pair of relatively wide and oppositely arranged end wrapper extensions, folding fingers movable while the carrier is at rest to tuck in the narrow extensions against an end of the article, a stationary abutment in the path of said extensions and arranged to first engage one of the wide extensions on movement of the carrier, actuating means for the fingers arranged to hold them between the wide extensions until the carrier has started on its next step of movement, whereby both wide extensions are independently folded in the same direction on movement of the carrier and each extension is separately creased along its line of fold.

9. In a wrapping machine, an intermittently movable carrier, two spaced walls therein between which a partially wrapped article may be positioned with an end wrapper extension projecting at right angles to one of said walls, a folding blade mounted to move transversely of and in close proximity to such wall to engage said extension and fold it flat thereagainst, means to move the partially wrapped article out of said carrier, and means to hold said blade in its moved position during the removal of the article.

10. In a wrapping machine, an intermittently movable carrier, two spaced walls therein between which a partially wrapped article may be positioned with an end wrapper extension projecting at right angles to one of said walls, a folding blade mounted to move transversely of and in close proximity to such wall to engage said extension and fold it flat thereagainst, means to eject the article from the carrier, and means controlled by the ejecting means to move said blade to folding position.

11. In a wrapping machine, an intermittently movable carrier, two spaced walls therein between which a partially wrapped article may be positioned with an end wrapper extension projecting at right angles to one of said walls, a folding blade mounted to move transversely of and in close proximity to such wall to engage said extension and fold it flat thereagainst, means tending to move said blade to folding position, intermittently operable means reciprocable toward and away from the pocket to eject the articles therefrom and arranged when at rest to hold said blade against movement by its actuating means, whereby when the ejecting means moves to eject the articles

the folding blade is moved to folding position and held there until the return of the ejecting means.

12. In a wrapping machine, an intermittently movable carrier having a pocket in which a partially wrapped article may be positioned with an end wrapper extension projecting substantially at right angles to one wall of the pocket, and means movable when the carrier is at rest to engage said extension and fold it flat against said wall.
13. In a wrapping machine, an intermitt-

tently movable carrier having a pocket in which a partially wrapped article may be positioned with an end wrapper extension 15 projecting substantially at right angles to one wall of the pocket, ejecting means to move the article out of the carrier, and means controlled by the ejecting means to fold said extension flat against said wall 20 during an interval of rest of the carrier.

ELMER L. SMITH.
ARTHUR E. PHELON.
